[57] CLAIM

The ornamental design for a cosmetic atomizer, substantially as shown and described.

DESCRIPTION

FIG. 1 is an elevational view of a cosmetic atomizer showing our new design, the opposite side being the same in appearance;

FIG. 2 is a top plan view;

FIG. 3 is a bottom plan view;

FIG. 4 is a sectional view taken on the line 4—4 of FIG. 1;

FIG. 5 is a sectional view taken on the line 5—5 of FIG. 1;

FIG. 6 is a top perspective view;

FIG. 7 is a bottom perspective view; and

FIG. 8 is an exploded perspective view thereof.
